US00D931301S

(12) **United States Design Patent** (10) **Patent No.:** **US D931,301 S**
Jang et al. (45) **Date of Patent:** **** Sep. 21, 2021**

(54) **DISPLAY SCREEN OR PORTION THEREOF WITH GRAPHICAL USER INTERFACE**

(71) Applicant: **Samsung Electronics Co., Ltd.,**
 Suwon-si (KR)

(72) Inventors: **Youngshil Jang**, Suwon-si (KR); **Yusic Kim**, Suwon-si (KR)

(73) Assignee: **SAMSUNG ELECTRONICS CO., LTD.**, Suwon-si (KR)

(**) Term: **15 Years**

(21) Appl. No.: **29/708,030**

(22) Filed: **Oct. 2, 2019**

Related U.S. Application Data

(62) Division of application No. 29/643,868, filed on Apr. 12, 2018, now Pat. No. Des. 868,089.

(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The outer perimeter shown in broken line in the drawings illustrates a display screen or portion thereof and forms no part of the claimed design. The remaining broken lines in the drawings illustrate portions of the graphical user interface that form no part of the claimed design.

1 Claim, 2 Drawing Sheets
